poration of New York

Application March 20, 1941, Serial No. 384,236

15 Claims.

(Cl. 33—49)

1

This invention relates to gun sights which are automatically displaceable relative to the gun in accordance with the rate of movement of the gun, and particularly to sights for guns that are mounted in fixed positions on a firing ship such as, for example, an airplane.

The directing of a gun fixedly mounted on an airplane has been a difficult problem because the gun has to be trained and elevated with reference to a target by adjusting the horizontal and azimuth position of the airplane and it was necessary for the pilot to approximate the angle that the airplane had to lead or point ahead of and above the target that the projectile would intercept the target.

The problem is further complicated because consideration has to be given to the changes in the rate of change of bearing of the target as a firing airplane closes in from one side on a moving airplane target.

The solution of the problem also involves the application of elevational movement of the sight relative to the gun to compensate for the rate of change in the vertical plane of space of the position of the firing airplane relative to the target and for the shape of the trajectory of the projectile, which is a function of the range.

The object of this invention is to provide an apparatus to position the sight relative to the bore of a gun, that is fixedly mounted in the horizontal plane of and parallel to the longitudinal horizontal axis of a firing airplane, in accordance with the instantaneous rates of change of bearing and elevation respectively of the target and the range of the target.

For the purpose of this specification and the appended claims the longitudinal horizontal axis of the firing airplane and the longitudinal horizontal axis of the casing supporting and housing the mechanisms are defined as the "center line of the airplane" and the "center line of the casing" respectively.

The particular mechanisms disclosed herein as embodiments of the invention are illustrative of mechanisms used to apply the invention to the problem of directing a gun fixedly mounted on one airplane firing on another airplane as a target, but it will be understood that the invention has other applications, such as directing a gun on any form of mount where the sight for directing the gun is displaced from the bore of the gun an amount depending upon the rate of angular movement of the gun or gun mount.

The mechanisms include an inertia element that inherently resists any change in its position in space, such as a gyroscope. The gyro is mounted on supporting arms and concentric rings and is free to rotate about its horizontal and its vertical mounting axes. The arms are mounted in a director casing or frame which is

2

pivoted to rotate about horizontal and vertical axes.

Two motors are mounted in the casing and connected through follow-up controls to maintain the centerline of the casing parallel to the spin axis of the gyro and at the same time to apply precessing forces to the gyro to cause the gyro to precess toward the centerline of the airplane at a rate directly proportional to the displacement of the centerline of the casing from the centerline of the airplane. The gyro is mounted in the casing with its spin axis parallel to the centerline of the casing when the gyro is in its mid or neutral position. A conventional sight is fixedly mounted in such a position on the casing that its optical axis is parallel to the centerline of the casing. It will thus be seen that when the casing is in its neutral position relative to the airplane or gun and the gyro is in its neutral position relative to the casing, then the centerline of the airplane, the optical axis of the sight, the centerline of the casing, and the spin axis of the gyro are all parallel to each other.

When such a gyro and casing with its associated sight are mounted in an airplane that is maneuvered to keep the sight pointed at another airplane or any other object as a target, any tendency for the airplane to change its position relative to the gyro is used to automatically determine the instantaneous rate of change of direction of the line of sight in the horizontal and vertical planes of space.

It is well known in the fire control art that the horizontal displacement of the sight from the bore of the gun (deflection or D_s) is directly proportional to the rate of change of bearing (dB) and the time of flight (t) of the projectile and that the time of flight of the projectile is a function of the range (R). This relation is expressed by the equation

$$Ds = dB \cdot R \text{ or } dB = \frac{Ds}{R} \quad (1)$$

From this equation it is seen that the rate of change of bearing is directly proportional to the deflection (D_s) and inversely proportional to the time of flight (t) or range (R). It is therefore to be understood throughout the specification and claims that the word range is intended to include a function of range or time of flight.

The motor, in the casing, which is connected to move the casing in azimuth to keep its centerline parallel to the spin axis of the gyro, applies the corresponding precessing force to the gyro through a dividing mechanism to cause the gyro to precess in azimuth at the rate dB , which, as shown by Equation 1 is directly proportional to the deflection (D_s) and inversely proportional to the range (R). The effect of this combination is to offset the centerline of the casing and there-

fore of the sight from the bore of the gun by the deflection (Ds) and to apply a precessing force to the gyro equal to the rate of change of bearing of the target, when the range (R) is set into the dividing mechanism. This precessing force acting on the gyro will cause the gyro to precess at the same rate the firing airplane must change heading or the gun must be trained or elevated, to keep the sight pointed at the target, while the sight is offset from the gun the proper amount to allow for the movement of the target during the time of flight.

The motion of the firing airplane through space does not enter into the problem as the velocity of the firing ship is merely additive to the initial velocity of the projectile, that is, the velocity of the projectile relative to the barrel of the gun.

It is also well known that when firing at an elevated target the vertical displacement of the sight from the bore of the gun (elevation or Es) is proportional to the rate of change of elevation (dE) and the time of flight (t) of the projectile, which is a function of the range (R). This relation is expressed by the equation

$$Es = dE \cdot R \text{ or } dE = \frac{Es}{R} \quad (2)$$

The second motor is therefore connected to apply a precessing force to the gyro directly proportional to the vertical displacement of the sight from the gun and inversely proportional to the range and to move the casing in elevation to keep its centerline horizontally parallel to the spin axis of the gyro.

Modifications of the invention are disclosed in one of which changes in rates, as indicated by movement of the follow-up motors, are utilized to displace the follow-up controls to cause the sight to be momentarily delayed in attaining its new position relative to the gun. The effect of this delay is that the operator senses any change in the rate of turning of the airplane or gun mount immediately upon changing the control.

A second modification discloses a connection from the motors to the gyro to cause the gyro to be precessed by movement of the motors in addition to the precessional rate applied to the gyro because of the rotary position of the motors or the sight relative to the gun. The effect of this second precessing force is to cause the gyro and the sight to be moved toward the target in addition to the movement due to the continuously applied precessing force.

The details of apparatus to accomplish the desired functions will now be described in detail.

In the drawings:

Fig. 1 is a plan view showing the positional relation of one airplane firing on another airplane as a target, as the firing airplane is closing in on the target from one side;

Fig. 2 is a horizontal cross-sectional view of the casing showing the mechanisms of the invention, taken on line 2-2 of Fig. 3;

Fig. 3 is a vertical cross-sectional view of the casing and mechanisms, in the simplest form, taken on the centerline 3-3 of Fig. 2, except that the gyro and the associated precessing arms are shown in elevation;

Fig. 4 is a vertical cross-sectional view of the casing and mechanisms taken on line 4-4 of Fig. 3;

Fig. 5 is a view similar to Fig. 4 taken on line 5-5 of Fig. 3;

Fig. 6 is a view similar to Fig. 3 but showing the added parts of one modification;

Fig. 8 is a view similar to Fig. 3 but showing the added parts of a second modification;

Fig. 9 is a vertical cross-sectional view of the casing and mechanisms taken on line 9-9 of Fig. 8, and

Fig. 10 is a wiring diagram showing the electrical connections.

With reference to Fig. 1, 1 represents an airplane having a gun 2 fixedly mounted parallel to the centerline of the airplane. The line 3 represents the direction of the line of sight relative to the centerline of the airplane 1, as the gun is being fired at another airplane or target 4. The line 5 represents the direction of the path of the firing airplane 1 and the direction of the path of the projectile to the intercept point 2a. The angle between the lines 3 and 5 is the deflection angle (Ds).

Referring to Figs. 2 to 5, inclusive, and particularly to Fig. 3, 6 represents a casing mounted for rotation about its transverse horizontal axis on ball bearings 7, 7 one of which is supported by trunnion 1a, upright brace 8 and frame 9, and the other of which is supported by frame 9. Frame 9 is mounted to rotate about its vertical axis in ball bearings 10 supported in base 11. Base 11 is mounted on some suitable support of the airplane with the lower face of base 11 in the horizontal plane of the airplane.

Access to the inside of the casing is had through openings 12 in the front and back walls of the casing 6. The openings 12 are covered by plates 13 secured to the casing 6 by bolts. A cover plate 13a is secured to frame 9 to protect the gearing mounted on the frame 9.

To the inside walls of casing 6 are secured two cross-straps 14 and 15 which act as supports for pivots 16 on which ring 17 is mounted. On the walls of casing 6 are also secured two arms 18 and 19, which act as supports for pivots 20 and 21 on which ring 22 is mounted. Pivotedly mounted in ring 22 is gyro 23.

The casing of the gyro 23 carries pins 24 which extend along the spin axis of the gyro and engage slots 25 in ring 17 whereby a rotational force is applied to ring 17 about its vertical axis to apply a force to gyro 23 to precess it about its horizontal axis on pivots 20 and 21. The rotational force is applied to ring 17 about its vertical axis by arm 26 which is rigidly connected to ring 17. The mechanisms to apply the force to arm 26 will be described hereinafter.

Also secured to ring 17 is arm 27 on the end of which is mounted a roller 28 which engages electrical contacts 29 which are insulated from each other and from a frame 30 to which they are secured. Frame 30 is held in position by bolting it to strap 15. The contacts 29 and roller 28 serve to control the deflection motor 31 the function of which will be described hereinafter. The roller 28 is connected to a power supply by the conductor 28'. The contacts 29 are connected to the motor 31 by the conductors 29' and the motor 31 is connected to the power supply by the conductor 31'.

There is attached to ring 22 an arm 32 by which a precessing force is applied to gyro 23 about its horizontal axis to precess it about its vertical axis. There is also connected to ring 22 an arm 33 on the end of which is mounted roller 34 which is connected to the power supply by a conductor 34'. Roller 34 cooperates with contacts 35 which

are insulated from each other and from an arm 36 on which they are supported. Roller 34 and contacts 35 serve to control elevation motor 37. The contacts 35 are connected to motor 37 through conductors 35' and motor 37 is connected to the power supply by conductor 37'. Arm 36 depends from arm 18.

Deflection motor 31 is connected by gears 38, 39, 40, 41, shaft 42, gears 43, shaft 44, gears 45, 46 and 47, to a circular, toothed plate 48 secured by bolts to base 11. It will thus be seen that motor 31 will drive the frame 9 and the supported mechanism in azimuth, that is, about its vertical axis.

Elevation motor 37 is connected by gears 49 and 50, shaft 51, and gear 52, to a toothed arcuate arm 53 extending downwardly from trunnion 1a which is secured against rotation in brace 8 by key 54. It will thus be seen that motor 37 will drive casing 6 about its transverse horizontal axis.

Referring particularly to Figs. 3 and 5, gear 41 previously described is also in mesh with rack teeth on slide 55 which is one input of a conventional divider 56. Slide 55 is supported in a grooved guide 55a secured to the walls of casing 6. The other input slide 57 of divider 56 is moved by gear 58 on shaft 59 which is set in accordance with the range of the target by either of the knobs 60. Dials 61 on shaft 59 cooperate with indices 62 to indicate the set-in value of the 30 range.

The output link 63 of divider 56 is located by the intersection of slides 55 and 57 in its central portion and is pivoted at its lower end on pin 64 which is secured by bolts to the arm 19. The output or upper end of link 63 is pivotally connected to slide 65 which moves in guide 66 secured to the walls of casing 6.

At the ends of slide 65 are mounted pins 67 and 68 which support spring 69. The center point of the spring 69 is connected to the upper end of arm 32 previously described.

The motion of motor 37 transmitted to shaft 51 is also transmitted to gear 70 which is pinned to shaft 51, and thence through gears 71 and 72 to slide 73, which is one input of a conventional divider 74. The other input to divider 74 is slide 75 which is set in accordance with the range by gear 76 connected to shaft 59 which is moved as previously described. The output link 77 of divider 74 is located by the intersection of slides 73 and 75 and is pivoted at its lower end on pin 78 secured to arm 18. The output end of link 77 is pivoted to slide 79 which moves in guide 80 secured to the walls of casing 6.

At the center of slide 79 is mounted pin 81 which is connected to the center of spring 82 the ends of which are connected to wire 83. Wire 83 passes over grooved pulleys 84 mounted on the top wall of casing 6. The center of wire 83 is connected to arm 26 previously described.

A conventional sight 85 is mounted on the top of casing 6 with its optical axis parallel to the centerline of the casing.

Operation (deflection)

If the firing plane 1 is flying straight ahead, the gyro, casing and sight will be automatically brought to their mid position parallel to the gun bore by the action of the motors 31 and 37 under the control of contacts 28-29 and 34-35 respectively. For example, if the gyro and casing are to the left of the mid position, a precessing force will be applied to the gyro to cause it to precess to the right at a reducing rate until the gyro 75

comes to the mid position when the rate will be zero and the sight will be parallel to the bore of the gun and the centerline of the airplane. Now, if the airplane is turning, say to the right, to follow and close in on a target in a relative position as indicated in Fig. 1, the spin axis of the gyro will tend to keep its position in space and there will be a relative counter-clockwise movement of the spin axis of the gyro from the centerline of the casing and the centerline of the plane. As a result of this relative movement roller 28 comes in physical contact with one of the electrical contacts 29 and motor 31 turns the casing 6 counter-clockwise about the base 11 through gears 39, 40, 41, shaft 42, gears 43, shaft 44, gears 45, 46 and 47, until the casing is moved to bring the centerline of the casing parallel to the spin axis of the gyro. At the same time the motor 31 applies a precessing force on the gyro 23, through gear 41, slide 55, divider 56, spring 69, and arm 32, proportional to the displacement of the sight from the bore of the gun divided by the range, until the clockwise rotational rate of the spin axis of the gyro is the same as the true clockwise movement of the airplane, when a balance is obtained and the proper deflection is set up in accordance with the equation $Ds = dB \cdot R$.

Operation (elevation)

The generation of the rate of change in elevation and the setting in of the correction in elevation is accomplished in the same manner as that for the rate of change of bearing and the deflection correction previously described.

The modification of the invention shown in Figs. 6 and 7 differs from that shown in Figs. 2 to 5 inclusive only in the action of the controls for the deflection and elevation motors, 31 and 37 respectively. Since the same numbers are used for corresponding parts their operation or construction will not be described except as the added parts of the modification affect their operation.

The difference in the controls is that the frame 30 and the arm 36, carrying the contacts 29 and 35 respectively, instead of being rigidly secured to cross strap 15 and arm 18 are yieldably mounted relative thereto and are displaceable from their normal central position in accordance with the speed and direction of rotations of the motors 31 and 37 by means of drag devices 86 and 87 respectively.

The drag device 86 consists of a shaft 88 carrying a disk 89 integral therewith. The frame 30 is secured to a hub 90 which is pinned to the shaft 88 and carries an arm 91 the outer end of which is normally centered by two springs 92 connected to eyes 93 in the side of casing 6. The upper end of shaft 88 is rotatably mounted in the cross strap 15 on the same axis as the pivot 16 and the lower end is mounted in cross strap 94.

The disk 89 is enclosed in a housing 95 which carries a gear 96 meshing with a gear 97 mounted to be rotated by deflection motor 31 through gears 38 and 39. The housing 95 is filled with oil or other liquid so that rotation of the housing by the motor causes a drag on the disk 89 which displaces the frame 30 and contacts 29 from their normal central position at which they are held by springs 92. This displacement is proportional to the speed of rotation of the motor 31.

The drag device 87 is similar to drag device 86 and consists of a shaft 98 having an integral disk 99 enclosed in a housing 100, one side of which is gear 72 driven by elevation motor 37 through gears 49, 50, 70 and 71. The shaft 98

is mounted at one end in casing 6 and at the other end in arm 18 on the same axis as pivot 20. The arm 36 is secured to a hub 101 which is pinned to shaft 98 and carries a second arm 102 the outer end of which is connected to springs 103 which are connected to eyes 104 mounted on the walls of casing 6. The housing 100 is filled with oil or other liquid so that rotation of the elevation motor 31 displaces the arm 36 and contacts 35 from their normally central position an amount proportional to the speed of the motor.

The displacement of the contacts 29 and 35 from their normal position relative to the casing due to the drag devices is in the direction the casing is moved by the motors 31 and 37 respectively, and an amount proportional to the speed of the motors.

The effect of this displacement on the operation is that when the operator changes the rate of change of course of the firing airplane to bring the sight on the target, the sight instead of being maintained continuously parallel to the spin axis of the gyro by the follow-up motors is displaced therefrom in the direction the operator is changing the rate of turning of the firing airplane and the operator therefore will see a temporary movement of the sight relative to the target in the same direction he is changing the rate of turning. Because of this movement the tendency of the operator to overcorrect the change of heading is reduced.

The modification of the invention shown in Figs. 8 and 9 differs from that shown in Figs. 2 to 5, inclusive, by the addition of a second precessing connection from each of the motors 31 and 37 to the gyro 23. In addition to the connections through the dividers 56 and 74 by which the gyro is caused to precess at a rate proportional to the displacement of the casing and sight from the bore of the gun, a second connection is provided from each motor including a drag device which applies a precessing force to the gyro in proportion to the rate of turning of the motor, which rate corresponds to the rate of movement of the casing and sight relative to the gun. The drag device 105 is actuated by the deflection motor 31 to apply forces to the gyro to cause precession in train and the drag device 106 is actuated by the elevation motor 31 to apply forces to the gyro to cause precession in elevation.

The drag device 105 consists of a drag disk 107 secured on shaft 42 which is rotated by deflection motor 31. A housing 108, enclosing disk 107, is free to rotate on shaft 42 and is filled with oil or other liquid. The housing 108 has a boss 109 on one side (see, Fig. 9) carrying a pin 110 to which is connected one end of a link 111, the other end of which is connected to a pin 112 on an arm 113 extending from ring 22.

The drag device 106 consists of a drag disk 114 integral with shaft 115 which passes through the cross strap 15 and is secured in ring 17, thereby forming the lower pivot for ring 17. The disk 114 is enclosed in a housing 116 which rotates on shaft 115 and is filled with oil or other liquid. The housing 116 carries a gear 117 meshing with a gear 118 on shaft 51 which is driven by elevation motor 31.

The effect of the drag devices of this modification on the operation of the sight is to cause the gyro and sight to be moved in space in the direction of the change of rate as determined by the follow-up contacts and the motors. For example, if the pilot is following a target so that the firing plane is turning to the right and the

pilot notices that the line of sight is falling behind the target, he will turn his airplane faster to the right which will cause the motor 31 to start to move the sight to the left relative to the gun and to increase the rate of training of the gyro to make its rate the same as the relative angular movement of the target. This change of rate of itself will not cause the sight to catch up with the target but the action of the drag device 105 will apply a second precessing force to the gyro due to the rotation of the motor 31 which force will cause the gyro to precess momentarily in the direction of the target. This precessing of the gyro is in addition to that applied through the divider 56.

It will be seen that whenever the sight moves off of the target the change of the rate of turning of the airplane made by the pilot will not only change the rate of continuous precessing of the gyro but will momentarily cause the gyro to precess additionally in a direction to bring the line of sight back on the target.

Similarly any movement of the sight from the target in elevation will be corrected both in rate and position by the pilot changing the rate of turning of the airplane in elevation.

While the invention has been described as applied to a sight for a gun fixedly mounted on an airplane, so that the rate of turning of the airplane to keep the sight on the target automatically displaces the sight from the gun the proper amount to allow for movement of the target during the time of flight, it is obvious that if the sight mechanism is secured to the gun cradle of any gun mount the movement of the mount to keep the sight on the target will automatically offset the sight the correct amount from the bore of the gun. Likewise the sight mechanism if mounted on a dummy gun cradle may be used as a director and the position of the dummy gun transmitted to the real gun may be used to position the real gun.

It is obvious that various changes may be made by those skilled in the art in the details of the invention as disclosed in the drawings and described above within the principle and scope of the invention as expressed in the appended claims.

We claim:

1. In combination with a manipulatable device, sighting means comprising a casing pivoted on the device for relative angular movement about a predetermined axis, a sight carried by the casing, a gyroscope universally mounted in the casing, a motor mounted on the casing and controlled by relative angular movement between the casing and the gyroscope about the predetermined axis, a connection between the motor and the device to impart angular movement to the casing relative to the device, means actuated by the motor for developing a force proportional to the angular rotation of the motor, and means for applying the force so developed as a precessional force to the gyroscope.

2. Directing means comprising a manipulatable support, a sight mounted on said support for universal pivotal movement, a gyroscope universally mounted on said support, an energy storing device operable to apply a precessional force to the gyroscope, a motor controlled by relative angular movement between the sight and the gyroscope and rotative in proportion to the angular displacement between the gyroscope and the support, means operated by the motor to impart energy into the energy storing device proportional

to the rotative position of the motor, and operative means between the motor and sight to adjust the angular position of the sight relative to the support proportional to the rate of angular movement of the support.

3. Directing means comprising a manipulatable support, a sight mounted on said support for universal pivotal movement, a gyroscope universally mounted on said support, an energy storing device operable to apply a precessional force to the gyroscope, a motor controlled by relative angular movement between the sight and the gyroscope and rotative in proportion to the angular displacement between the gyroscope and the support, means operated by the motor to impart energy into the energy storing device proportional to the rotative position of the motor, operative means between the motor and sight to adjust the angular position of the sight relative to the support proportional to the rate of angular movement of the support, and means for modifying the proportion between the rotative position of the motor and the energy imparted to the energy storing device by the motor.

4. A sight mechanism for a gun fixedly mounted on an airplane, comprising a casing mounted on the airplane for angular adjustment about two axes, a sight carried by the casing, a gyroscope in the casing mounted for freedom of movement about two axes substantially parallel to those of the casing, two motors connected to adjust the angular position of the casing about the respective axes, control means for the motors operative in response to relative angular movement between the casing and the gyroscope about the respective axes, means actuated by each motor for developing a force proportional to the angular adjustments of the casing relative to the gun about the respective axes, and means for applying the forces so developed as precessional forces to the gyroscope to cause precession of the gyroscope about the respective axes.

5. A sight mechanism for a gun fixedly mounted on an airplane, comprising a casing mounted on the airplane for angular adjustment about two axes, a sight carried by the casing, a gyroscope in the casing mounted for freedom of movement about two axes substantially parallel to those of the casing, two motors connected to adjust the angular position of the casing about the respective axes, control means for the motors operative in response to relative angular movement between the casing and the gyroscope about the respective axes, means actuated by each motor for developing a force proportional to the angular adjustment of the casing relative to the gun about the respective axes, means for applying the forces so developed as precessional forces to the gyroscope to cause precession of the gyroscope about the respective axes, and means for modifying the proportion between the adjustment of the casing and the forces developed.

6. A sight mechanism for a gun fixedly mounted on an airplane firing at a target, comprising a base mounted on the airplane with its vertical axis parallel to the vertical axis of the airplane, a frame mounted on the base for rotary movement about a vertical axis parallel to the vertical axis of the base, a casing pivotally mounted on the frame for rotation about a transverse horizontal axis, a sight mounted on the casing with its optical axis parallel to a centerline of the casing, a gyroscope universally mounted in the casing with its spin axis and its vertical mounting axis parallel respectively to the centerline of the

casing and the vertical axis of the frame when the gyroscope is in its neutral position relative to the casing, power means mounted in the casing, means actuated by relative angular movement between the gyroscope and the casing for controlling the power means, means connecting the power means to the base for rotating the frame and the casing about the vertical axis, and means connecting the power means to the gyroscope for applying forces to the gyroscope to precess it about its vertical axis at a rate proportional to the rate of angular movement of the airplane about its vertical axis including means settable in accordance with the range of the target.

7. A sight mechanism for a gun fixedly mounted on an airplane firing at a target, comprising a base mounted on the airplane with its vertical axis parallel to the vertical axis of the airplane, a frame mounted on the base for rotary movement about a vertical axis parallel to the vertical axis of the base, a casing pivotally mounted on the frame for rotation about a transverse horizontal axis, a sight mounted on the casing with its optical axis parallel to a centerline of the casing, a gyroscope universally mounted in the casing with its spin axis and its vertical mounting axis parallel respectively to the centerline of the casing and the vertical axis of the frame when the gyroscope is in its neutral position relative to the casing, power means mounted in the casing, means actuated by relative angular movement between the gyroscope and the casing for controlling the power means, means connecting the power means to the frame for rotating the casing about its transverse horizontal axis, and means connecting the power means to the gyroscope for applying forces to the gyroscope to precess it about its horizontal axis at a rate proportional to the rate of angular movement of the airplane about its horizontal transverse axis including means settable in accordance with the range of the target.

8. A sight mechanism for a gun fixedly mounted on an airplane firing at a target, comprising a base mounted on the airplane with its vertical axis parallel to the vertical axis of the airplane, a frame mounted on the base for rotary movement about a vertical axis parallel to the vertical axis of the base, a casing pivotally mounted on the frame for rotation about a transverse horizontal axis, a sight mounted on the casing with its optical axis parallel to a centerline of the casing, a gyro universally mounted in the casing with its spin axis and its vertical mounting axis parallel respectively to the centerline of the casing and the vertical axis of the frame when the gyro is in its neutral position relative to the casing, power means mounted in the casing, means actuated by relative angular movement between the gyro and the casing for controlling the rotation of the power means in accordance with the angular position of the spin axis of the gyro relative to the gun, transmission means connecting the power means to the base and to the frame for rotating the frame and the casing about their vertical and transverse horizontal axes respectively, and transmission means connecting the power means to the gyro to apply forces to the gyro to cause precession about its vertical and its horizontal axes at rates proportional to the rates of angular movement of the airplane about its vertical and horizontal transverse axes, respectively, the connecting

means including means settable in accordance with the range of the target.

9. A sight mechanism for a gun fixedly mounted on an airplane firing at a target, comprising a base mounted on the airplane with its vertical axis parallel to the vertical axis of the airplane, a frame mounted on the base for rotary movement about a vertical axis parallel to the vertical axis of the base, a casing pivotally mounted on the frame for rotation about a transverse horizontal axis, a sight mounted on the casing with its optical axis parallel to a centerline of the casing, a gyro universally mounted in the casing with its spin axis and its vertical mounting axis parallel respectively to the centerline of the casing and the vertical axis of the frame when the gyro is in its neutral position relative to the casing, train and elevation power means mounted in the casing, means actuated by relative angular movement between the gyro and the casing for controlling the rotation of the power means in accordance with the angular position of the spin axis of the gyro relative to the gun, a pair of mechanical dividing means settable in accordance with the range of the target, means for connecting the respective power means to the respective dividing means, and means for connecting the output of the respective dividing means to the gyro for applying forces to the gyro, whereby the gyro is precessed about its vertical axis and its horizontal axis at rates proportional to the angular position of the spin axis of the gyro relative to the gun and inversely proportional to the range of the target.

10. In combination with an angularly movable gun, sighting means comprising a casing pivoted for angular adjustment relative to the gun, a sight carried by the casing, a gyroscope universally mounted in the casing, a motor connected to adjust the angular position of the casing relative to the gun, means actuated by the motor for developing a force proportional to the angular adjustment of the casing relative to the gun, means for applying the force so developed to the gyroscope as a precessing force, and control means for the motor actuated by angular movement of the gyroscope relative to the casing, said control means including a part displaceable in accordance with the speed of the motor and operable to delay the action of the motor in adjusting the angular position of the casing relative to the gun.

11. A sighting mechanism for an angularly movable gun, comprising a casing mounted for angular adjustment relative to the gun about two mutually normal axes, a sight carried by the casing, a gyroscope mounted in the casing for angular movement about two axes normally parallel to those of the casing, two motors connected to adjust the angular position of the casing relative to the gun about the respective axes, means actuated by the respective motors for developing forces proportional to the angular adjustment of the casing relative to said gun about each of the axes, means for applying the forces to the gyroscope to cause precession of the gyroscope about the respective axes, control means for each of the motors actuated by angular movement of the gyroscope relative to the casing about the respective axes, each of said control means including a part displaceable by and in accordance with the speed of the controlled motor and operating to delay the action of the motor in adjusting the angular position of the casing relative to the gun about the respective axes.

12. A sighting mechanism for an angularly movable gun, comprising a sight mounted for angular adjustment relative to the gun about two mutually normal axes, a gyroscope mounted for angular movement about two axes normally parallel to those of the sight, two motors connected to adjust the angular position of the sight relative to the gun about the respective axes, means actuated by the respective motors for developing forces proportional to the angular adjustment and the rate of angular movement of the sight relative to said gun about the respective axes, means for applying the forces to the gyroscope to cause precession of the gyroscope about the respective axes, and control means for each of the motors actuated by angular movement of the gyroscope relative to the sight about the respective axes.

13. A sighting mechanism for an angularly movable gun, comprising a sight mounted for angular displacement relative to the gun, a gyroscope mounted for angular displacement relative to the gun, power means operable in response to differences in the angular displacements of the sight and the gyroscope relative to the gun to adjust the angular displacement of the sight relative to the gun, means actuated by the motor for developing a force proportional to the angular displacement of the sight from the gun, and means for applying the force to the gyroscope to cause precession of the gyroscope in the direction of movement of the gun and at a rate proportional to the force.

14. A sighting mechanism for an angularly movable gun, comprising a sight mounted for angular displacement relative to the gun, power means operable to angularly displace the sight relative to the gun, a gyroscope mounted for angular displacement relative to the gun, means actuated by the power means for developing a force proportional to the angular displacement of the sight from the gun, means for applying the force to the gyroscope to cause precession of the gyroscope in the direction of movement of the gun at a rate proportional to the force, and control means for said power means actuated by relative displacement between the sight and the gyroscope, whereby the sight and the gyroscope are displaced from the gun proportionally to the rate of movement of the gun, said control means including means to delay the operation of the power means in proportion to the rate of movement of the power means.

15. A sighting mechanism for an angularly movable gun, comprising a sight mounted for angular displacement relative to the gun, a gyroscope mounted for angular displacement relative to the gun, power means operable to maintain the sight parallel to the spin axis of the gyroscope, means actuated by the power means for developing a force proportional to the angular displacement of the sight and the gyroscope from the gun, means for applying the force to the gyroscope to cause precession of the gyroscope in the direction of movement of the gun and at a rate proportional to the force, means for developing a force proportional to the rate of change of displacement of the sight and the gyroscope relative to the gun, and means for modifying the effect of the first mentioned force on the gyroscope by an amount proportional to the last mentioned force during changes of displacement of the sight and gyroscope relative to the gun.
